UNITED STATES PATENT OFFICE.

ALBERT O. QUINBY AND THOMAS H. BATES, OF FRESNO, CALIFORNIA.

DESIGN FOR A MEDAL.

SPECIFICATION forming part of **Design No. 21,703, dated July 12, 1892.**

Application filed June 4, 1892. Serial No. 435,566. Term of patent 3½ years.

To all whom it may concern:

Be it known that we, ALBERT O. QUINBY and THOMAS H. BATES, citizens of the United States, residing at Fresno, in the county of Fresno and State of California, have invented and produced a new and original Design for a Medal, of which the following is a full, clear, and exact specification.

Reference is to be had to the accompanying drawing, forming a part of this specification, in which the figure represents a face view of a medal embodying my new design.

The medal is in the nature of a souvenir of the Chicago World's Fair, and the essential feature consists in a circular body having thereon the representation of a spread-eagle

surmounting a shield-like figure bearing a bird's-eye view of the exposition-buildings.

The minor features consist of the novel marginal lines of the shield, in which scallops ²⁰ *a* appear, forming the points *a'*, the ends of the side marginal lines terminating at top and bottom in scrolls *b*.

We claim—

The design for a medal herein shown and ²⁵ described.

ALBERT. O. QUINBY.
THOS. H. BATES.
